UNITED STATES PATENT OFFICE.

EDWARD G. THOMAS, OF BROOKLINE, MASSACHUSETTS.

BELT CONVEYER.

No. 857,772.

Specification of Letters Patent.

Patented June 25, 1907.

Application filed October 19, 1906. Serial No. 339,629.

To all whom it may concern:

Be it known that I, EDWARD G. THOMAS, of Brookline, county of Norfolk, State of Massachusetts, have invented and produced 5 certain new and useful Improvements in Belt Conveyers, of which the following is a specification.

The transportation of material of all kinds by means of moving belts supported by rotatable rollers, is an extensive practice in all 10 branches of the arts. When this device is applied to the carrying of granulated material, the amount which can be transported is limited, by the tendency of the material to 15 spread to the edge of the belt and fall from it. No greater amount can be carried than that which will form a pile, highest in the center of the belt and having an angle of repose, under the operating conditions of the belt, in- 20 sufficient to cause the edge of the pile to extend to the edge of the belt. In order to increase the capacity of a given width of belt, it is common practice to raise the edges of the belt above the center by means of in- 25 clined rollers, usually termed "troughing idlers." When this is done, it is obvious that a greater amount of material can be placed on belt before the edges of the pile will ex- 30 tend to the edges of the belt. When trough- 35 ing idlers, consisting of two or more pulleys, turning on axes inclined to one another, are used, the belt is forced by its weight and that of its load to make a bend at the point where the surfaces of the pulleys meet, as each por- 40 tion of the belt passes over the idlers, while between them the belt will take a flatter and more evenly distributed curve. A bending strain, due to a forward and back motion, is therefore put on that portion of the belt 45 which registers with the meeting angle of the pulleys, as many times per minute as the distance between idlers is contained in the speed of the belt per minute. The result of this repeated strain concentrated along a line of 50 the belt, is the rapid destruction of the belt on this line long before other portions of the belt are worn out. A variety of devices for adding to the strength, or increasing the pli- 55 ability of the belt at these points of greatest wear, have been tried with varying degrees of success.

My invention consists in substituting for the pulleys, set at an angle, ordinarily used, under the side of the belt on which the load 55 is placed (usually called the "working side") in contradistinction to the lower part or "re-

turn side"), a flexible troughing roller sup- 60 ported at the ends in bearings, in combina- 65 tion with a supporting roller, mounted in bearings placed below and to one side of the 60 bearings for the troughing roller. The rela- 70 tive diameters of the flexible troughing roller and the supporting roller are such that the flexible roller must sag in the center, be- 75 fore a belt placed upon the idler can come in contact with both rollers. A preferable con- 80 struction will be such that the weight of the belt and load will be sufficient to cause a suf- 85 ficient sagging of the flexible troughing roller to permit the belt to come in contact with, 90 and be supported for a part of its width by the lower roller. Inasmuch as this contact will occur at the center of the belt, it is ob- 95 vious that the greater part of the weight of the belt and its load will be supported by 100 this lower roller, while the flexible troughing roller will serve to bend upward the edges of the belt into the troughed form desired.

My invention is illustrated by the drawings which accompany and form a part of these 105 specifications.

In these drawings Figure 1 is a side eleva- 110 tion of the idler, showing the belt in cross section, illustrating the position occupied by its parts, when the belt is loaded with mate- 115 rial. Fig. 2 is an end elevation of this idler, showing a portion of side view of belt.

In these drawings 1 is a flexible roller, formed preferably by a steel spring. Each end of this roller 1 is secured to a rotatable 120 flange 2, in which the axially projecting ends of the spring can be securely fastened. Said flange 2 is supported by box 3, which is pivotally mounted in a supporting bracket 4, secured to the frame-work 7 of the con- 125 veyer. A roller or pulley 5 is rotatably mounted in bearings 6, below and to one side of the bearings for the flexible roller. The bearings 6 are secured to the frame-work 7 130 of the conveyer. The conveyer belt is 140 marked 8.

I prefer in the construction of this device to put the spring roller in place with a slight initial tension, so that the bearings 3 will be thrust bearings at all times. These bearings 145 are pivoted in order that the ends of the spring roller may occupy positions varying according to the deflection of the roller. In- 150asmuch as the length of the spring will be increased as it is deflected by the weight of 155 the belt and load, the tension of the spring and its supporting force will increase with

an increase of load upon the belt, but it is presumed that the greater part of the weight of the belt and load will be supported upon the lower roller 5.

5 There will obviously be no point along the spring roller at which a sharp bend will occur, so that the belt will be bent at an easy curve, and no point will be strained beyond the ability of the belt to stand the work.

10 The roller 5 may consist of a flexible roller similar to the troughing roller, in which case it will be of greater strength than the troughing roller, so as to have less deflection under load. A preferred construction is, however, 15 to make the roller 5, from one or more inflexible rollers or pulleys, rotatable on a stationary shaft, or from one or more pulleys secured to a rotatable shaft. Under a reasonable constant load the pivots for boxes 3 20 may be omitted and the boxes secured in a fixed inclined position, but for variable loads it will be desirable to follow the construction shown in the drawing.

Having thus fully described my invention, 25 I desire to claim and secure by Letters Patent of the United States the following:—

1. In a belt conveyer the combination of a belt, belt-supporting rollers and flexible belt-troughing rollers, in adjacent contact with 30 the load-carrying side of said belt, substantially as described.

2. In a belt conveyer the combination of a belt, a belt-supporting roller, and a flexible belt-troughing roller, said supporting roller 35 being pivoted below and to one side of the

bearing for said troughing roller, substantially as described.

3. In a supporting device for the load-carrying side only of belt conveyers the combination of a belt-supporting roller and a flexible belt-troughing roller, substantially as described. 40

4. In a supporting device for the load-carrying side of belt conveyers the combination of a belt-supporting roller and a flexible belt-troughing roller, said supporting roller being pivoted below and to one side of said troughing roller, substantially as described. 45

5. In a supporting device for the load-carrying side of belt conveyers the combination of a belt-supporting roller, bearings for said roller, a flexible belt-troughing roller, bearings for said troughing roller and supporting means for all said bearings, substantially as described. 50

6. In a supporting device for the load-carrying side of belt conveyers the combination of a belt-supporting roller, bearings for said roller, a flexible belt-troughing roller, pivoted bearings for said troughing roller and supporting means for all said bearings, substantially as described. 55

In testimony whereof I have signed my name to this specification in the presence of the two subscribing witnesses.

EDWARD G. THOMAS.
